[57] **CLAIM**

I claim the ornamental design for a visor, as shown.

DESCRIPTION

FIG. 1 is a perspective view from the top, front, and right side of a visor showing my new design;

FIG. 2 is a left side view thereof;

FIG. 3 is a top view thereof;

FIG. 4 is a front elevational view thereof;

FIG. 5 is a bottom view thereof; and,

FIG. 6 is a rear elevational view thereof.

The broken line showing of the human form in FIG. 1 is for illustrative purposes only and forms no part of the claimed design.
